MATERNITY GARMENT

Arlene J. Greendale, Chicago, Ill.

Application October 9, 1948, Serial No. 53,629

1 Claim. (Cl. 2—76)

1

The invention relates to improvements in garments and more particularly to a novel fitted maternity garment.

Dresses of the kind intended for use as maternity garments often are fashioned with shirring or pleats in the area of the waist, at least in the frontal region, so as to permit progressive expansion of the garment at the waist area. Other such garments are fashioned in the manner of wrap-arounds; that is, they are open their entire length and are adapted to initially overlap at the opening, with sufficient overlap material as will permit progressive reduction in the overlap without exposing the opening.

Garments embodying these and other known features enabling expansion are unattractive, owing principally to the failure to provide means to permit necessary expansion without destroying the basic lines of a fitted garment. As an example, a garment having a shirred waist has too much fullness in the depending skirt portion, while in the wrap-around type of garment no attempt is made to maintain the semblance of a fitted dress.

The present invention has as one of its objects the provision of a readily expansible form-fitted garment.

Another object of the invention is to provide a form-fitted garment with an expansible frontal area.

Another object of the invention is to provide a form-fitted garment with novel means permitting progressive expansion of the frontal waist area without causing the remaining portions of the garment to become unsightly because of sagging, excessive fullness or tautness.

Another object is to provide novel means for securing adjustable areas of a garment taut without binding.

Other and further objects of the present invention will be apparent from the following descriptions and claim, and are illustrated in the accompanying drawing which, by way of illustration, shows an exemplary embodiment and the principles thereof. Other embodiments of the invention embodying the same principles may be used, and structural changes may be made as desired by those skilled in the art, without departing from the present invention and the purview of the appended claim.

In the drawing:

Fig. 1 is a front elevational view of a garment embodying the features of the present invention.

Fig. 2 is an enlarged fragmentary front elevational view of the waist of the garment.

2

Fig. 3 is a fragmentary inside elevational view of the garment front, at the waist area.

Referring specifically to the accompanying drawing, the garment of the present invention includes a skirt 11 and a bodice 12, suitably joined at the waist in a seam 13. Shoulder straps 14, or the like, may be affixed to the upper margin of the bodice 12. The waist seam 13 extends substantially about the entire garment, but the stitching thereof terminates short of the frontal area so as to leave an unsewn portion defining a waist slit or opening 15.

The skirt 11 may be fabricated in any suitable or conventional manner. However, in the form-fitted garment of the present invention, at least the front area consists of a plurality of gores 16, connected in seams 17 along complementary adjacent edges. The seams 17 extend from the lower edge of the skirt in the direction of the waist seam 13. The seams 17 terminate short of said waist seam, as at 18, to thereby leave the upper extremities of the gores unsecured and provide flaps 19.

The bodice portion 12 likewise is fabricated from a plurality of sections 20 suitably joined along complementary adjacent edges in seams 21. The seams 21, like the seams 17, also terminate short of the waist seam 13, so as to leave the lower extremities of the sections 20 free to define flaps 22. Upon referring to Fig. 3, it will be observed that the side edges of the flaps 19 and 22 are suitably folded over and bound, as by tape 23. This provides a finished appearance to the flap edges and further provides required reinforcement for the flaps to prevent their being readily stretched or otherwise drawn out of their intended shape. Each of the free end edges of the flaps 19 and 22 is suitably provided with a hem 24, which hems are reinforced and finished by binding tape 25. The hems 24 are open at their ends and are adapted to receive therethrough a draw string generally indicated at 26.

The draw string 26 may include a pair of laces 27 formed by folding the draw string medially upon itself and securing its bight portion to the inside face of the garment at one end of the waist slit 15, as by means of stitches 28. If desired, two separate laces, tied at both ends, may be used. The laces 27 are then threaded in the manner illustrated so as to be crossed over, as at 29, between adjacent flaps. In this manner the flaps of the skirt are afforded adequate support by the lacing so as to prevent their sagging or becoming displaced laterally with relation to the companion flaps on the bodice 12. The free ends

of the laces 27 may be brought through an eyelet 30 and suitably tied, as at 31, in any position of adjustment; or the eyelets may be omitted and the ends may be tied on the inside of the garment, in which event the ties 31 are concealed.

It should be quite obvious at this time that a form-fitted garment constructed as described hereinbefore is capable of having its frontal area at the waist expanded or contracted easily and quickly, without shirring or wrinkling, and that the portions thereof affording such expansion or contraction are adequately held against displacement so as to thereby insure correct hanging of the skirt 11, without undue flaring or other bulkiness. It should be understood further that the garment disclosed herein is adapted to constitute one portion of an ensemble, the other portion consisting of a suitable jacket (not shown), which, when worn, will conceal the openings resulting from expansion of the frontal area.

Although an exemplary form of the invention has been shown in the accompanying drawing and described in detail in the foregoing specification, it should be understood that the garment is capable of embodying a variety of modifications in detail structure and assembly, such as the providing of darts as continuations of the perpendicular slits in a form-fitted skirt and bodice

formed without the gores and sections illustrated, without departing from the spirit of the invention or scope of the appended claim.

I claim:

- 5 A garment including a skirt and bodice joined by a waist seam terminating at either side of the medial front area so as to leave unsecured waist edges in said area, said waist edges having a plurality of oppositely disposed slits perpendicular 10 to said edges, said edges and slits defining in said front area a plurality of oppositely disposed flaps, a hem in the waist edge of each flap, means reinforcing the flaps along the edges of the slits, and a draw string laced through all of said hems.
